C. H. ROBINSON.

Lamp.

No. 35,955.

Patented July 22, 1862.

UNITED STATES PATENT OFFICE.

CHARLES H. ROBINSON, OF BOSTON, MASSACHUSETTS.

IMPROVEMENT IN LAMPS.

Specification forming part of Letters Patent No. 35,955, dated July 22, 1862.

To all whom it may concern:

Be it known that I, CHARLES H. ROBINSON, of Boston, in the county of Suffolk and State of Massachusetts, have invented an Improvement in Lamps; and I do hereby declare that the following is a full and exact description thereof, reference being had to the accompanying drawings, and to the letters and figures marked thereon.

Figure I is a perspective and sectional view. Fig. II is a section of the central part of the lamp. Fig. III is a plan of the wick and tube, the button being removed. Fig. IV is a plan of the wick-tube and cross-bar. Fig. V is a plan of the case formed by the outer and inner tubes.

My improvements relate to lamps having a circular wick and in which air is supplied to the interior of the wick in the same manner as in the Argand lamp, the main features of my invention consisting in this, first, in causing the metallic cylinder inclosed within the wick to rise and fall, carrying the wick with it, instead of raising or lowering the wick only, as has been heretofore practiced; second, the height of the flame is regulated by a button or disk having a vertical motion in combination with a circular wick and tube, also moving vertically, the wick and button being so arranged as to receive a simultaneous motion when the adjusting-screw is turned. By this combined action the top of the wick, when raised or lowered, is always at the same distance from the button.

The lamp is intended chiefly for burning kerosene or coal oils, but may be used for other kinds of oil.

In Fig. I the circular vessel containing the oil is shown at A, the interior part surrounding the tubes being so formed as to direct the rising current of air through the conical cap U, and cause it to impinge upon the outside of the circular wick K. A current of air also flows through the holes E in the dripping-cup C at the base of the lamp and ascends through the inside of the fixed central tube, Q, to the inside of the wick, thence the combined currents strike the button or disk I, which is of about the same diameter as the outside tube, H. This button is supported upon the top of a small wire, L, that passes down through the

center and is soldered to the screw F, the thread of which plays in the bottom of the dripping-cup C. By turning this screw at the milled head G the wire L and button I are raised or depressed.

The description thus far relates to parts heretofore known, the button and screw being used in camphene and fluid lamps for regulating, to a certain extent, the height of the blaze. My improvements relate to the central tubular parts which are thus constructed.

The outer and inner tubes, H and Q, are joined at the base, at which point they are screwed to the top of the dripping-cup. These tubes are concentric, and the inner one is about an inch shorter than the outer one. The difference in their diameters is about one-fourth of an inch, or sufficient to form an annular space, J, wide enough to receive the movable wick-tube P and the wick K. A flat bar, S, extends from side to side of the inner fixed tube near its top, and has a hole at its center, through which a circular collar, M, that is made fast to the central wire, L, traverses. The wick-tube P is of the same length as the outer tube of the case H Q, and the circular wick is slipped upon it and retained by friction, the tube and wick nearly filling the annular space J, as above mentioned. A flat bar, N, is also soldered to the inside of the wick-tube near its top, and has at its center a hole, T, in which the central wire, L, can play without friction. When the wick-tube is dropped into the case, the lower side of this bar rests upon the top of the collar M. The button I is then placed upon the top of the wire L and the lamp is ready for lighting, the oil B being supplied from the vessel A through the feeding-tubes W and W', passing through the outer tube, H, of the case H Q.

The height of the button above the top of the wick-tube is adjusted (by lengthening or shortening its supporting-wire) to the point that will give the best flame, and when this is attained the collar M should just touch the cross-bar of the wick-tube, as represented in Fig. II.

When the flame grows dim from incrustation or other cause, the screw F is turned, which raises the button and wick-tube, thus exposing a new portion of the wick, and at the

same time retaining the top of the wick and the button at the same distance apart as before.

What I claim, and desire to secure by Letters Patent, is—

1. The wick-tube and wick moving vertically together, instead of moving the wick alone, as heretofore practiced.

2. The simultaneous vertical motion of the

wick-tube and button, by which their distance apart is always kept uniform, by means of the screw and attached parts, as herein fully described, or their equivalents.

CHARLES H. ROBINSON. [L. S.]

In presence of—

SAM'L. BATCHELDER, Jr.,

J. M. BATCHELDER.
